This invention relates to an improved cigarette lighter and dispenser, and has for one of its principal objects the provision of means whereby a cigarette or cigar can be practically simultaneously lighted and dispensed from a container at a single motion of the operator or user.

One of the important objects of the invention is to provide in a combined cigarette lighter and dispenser, means for lighting the cigarette or cigar, which means also has in connection therewith and forming part thereof, elements for dispensing the same from a container in which the cigarettes or cigars are kept about the person of the user.

Another and still further important object of the invention is to provide in a combination cigarette lighter and dispenser, means for automatically lighting the cigarette as it is dispensed, and additional means for automatically extinguishing the lighting flame after the same has served its purpose.

Other and further important objects of the invention will be apparent from the disclosures in the accompanying drawings and following specification.

The invention, in a preferred form, is illustrated in the drawings and hereinafter more fully described.

In the drawings:

Figure 1 is a plan view of the interior of a cigarette or cigar container showing the improved automatic lighting and dispensing elements of this invention associated therewith.

Figure 2 is an exterior view illustrating the operating lever or trip.

Figure 3 is a sectional view taken on the line 3-3 of Figure 1, looking in the direction indicated by the arrows.

Figure 4 is a sectional view taken on the line 4-4 of Figure 1, looking in the direction indicated.

Figure 5 is a sectional view somewhat similar to Figure 4, but showing the parts in a different operating position.

Figure 6 is a plan view, parts being broken away and omitted, illustrating a slight modification of the invention.

As shown in the drawings:

The reference numeral 10 indicates the

container, forming an essential part of the improved cigarette lighter and dispenser of this invention, the same having a cover 12 affixed thereto by means of hinges or the like 14.

The container is long as shown, thereby affording space for a plurality of cigars or cigarettes therein, the same adapted to be ejected singly through an opening 16 in the side of the container, the same being normally closed by a manually operated slide 18.

The cigarettes as shown in the dotted lines at 20 are adapted to light in dispensing position against the wall of the container 22 which is kept filled with lighting fluid and which has a wick 24 fitted thereto at one end. Adjacent the wick is the ordinary flint 26 and steel wheel 28 by means of which the wick is lighted, the wheel 28 being mounted on a shaft 30 fixed in suitable supporting brackets 32, the shaft having also fitted thereto a gear wheel 34 which is in mesh with a rack 36, the rack being integral with an operating rod having a push button 38 at the outer end thereof, the push button being positioned outside the container 10.

The rack bar 36 extends into a cylinder 40 fitted in the container 10 adjacent the fuel tank 22 and at the lower end of the rod is fitted a piston 42, which is normally impelled outwardly by means of a helical spring 44 fitted in the lower end of the cylinder.

The rack bar 36 has an integral projection 46 thereon, this projection being flat on one side to co-operate with a trigger 48 which forms the inner end of the pivoted trip bar 50, the last-named bar extending outwardly through the side wall of the container 10.

A leaf spring 52, having a curved surface, to co-operate with the lower cammed face of the projection 46, is mounted adjacent the rack bar 36, and when the rack bar is pushed downwardly after a releasing operation, the cam surface 46 rides beneath the curved end of the leaf spring 52 which then forces the trigger element 48 into position as shown in Figure 1, leaving the device ready for another operation.

The rack bar 36 also comprises a pair of integral lugs 54, set close together as shown

in Figure 1, and between these lugs is positioned a pin or the like set into the outer end of a bar 56 pivotally mounted at 58 to the bracket 32.

- 1. The other end of the bar 56 has integral therewith a cigarette expelling paddle or blade 60, and adjacent this blade 60 is a guard or guide plate 62. A slot is formed in the end of the bar 56 and a pin is positioned in this slot, the pin being affixed to the upper end of a connecting link 64 which is pivotally mounted at its lower end to a snuffing sleeve or the like 66 which is fitted over the wick 24.
- 2. Upon release of the trip 50, the spring 44 will impel the rack member 36 outwardly rotating the gear wheel 34 and its attached steel wheel 28 whereupon sparks from the flint 26 will ignite the wick 24. The wick 24 will by this time be uncovered as the outward action of the rack member 36 will force the snuffing sleeve 24 downwardly into the position shown in Figure 5, whereupon the wick will be lighted. At the same time, the cigarette passing over the flame will be lighted, and its end will project outwardly through the opening 16 to a sufficient distance to allow it to be grasped by the operator and withdrawn after it has become lighted, whereupon the rod 36 being pushed inwardly by a manual operation of the knob 38 and the device is ready for another lighting and dispensing operation.

3. A slight modification is shown in Figure 6 wherein the wick 70 is lighted by a flint and steel operated by the rack bar 76 in the same manner as above described, this rack bar, however, having an integral extension 78 in which is fitted a pin 80 projecting sidewise to a sufficient distance to act upon the rear face of an L-shaped arm 82 which is pivotally mounted in the casing at 84.

4. This L-shaped arm is maintained in retracted position by means of a spring 86 and as the rack bar 76 is impelled upwardly, the pin 80 forces the L-shaped bar forwardly into a cigar ejecting position.

5. It will be evident that herein is provided a compact and simple, yet efficient device for automatically lighting and dispensing a cigarette or cigar upon a single releasing operation which is merely the pressure upon a trigger or latch. Further, a resetting of the device automatically extinguishes the flame by means of which the cigar or cigarette has been lighted, thereby providing a very safe apparatus.

6. I am aware that many changes may be made and numerous details of construction varied throughout a wide range without departing from the principles of this invention, and I, therefore, do not purpose limiting the patent granted hereon otherwise than as necessitated by the prior art.

I claim as my invention:

- 1. A cigarette lighter and dispenser, com-

prising in combination, a container for cigarettes, an automatically operated lighting element in the container, a wick at one end of the lighting element, a flint and steel adjacent the wick, a shaft upon which the wheel is mounted, a gear fitted on the shaft, a vertically movable rack in mesh with the gear, an operating rod integral with the rack, a push-button at one end of the operating rod outside of the container, a piston mounted on the other end of the rack bar, a cylinder in which the piston is slidably fitted, a helical spring in the cylinder below the piston, a projection integral with the rack bar, a trigger adapted to cooperate with said projection, and a trip bar for the trigger extending outwardly through the side wall of the container, together with a leaf spring adapted to cooperate with the lower face of the projection, said leaf spring having a curved end allowing the projection to ride beneath the same upon downward movement, and latching the same upon initiation of an upward movement, a pair of integral lugs on the rack bar, a lever pivotally mounted adjacent the rack bar, a pin in one end of the lever between the lugs, and a cigarette expelling paddle at the other end of the lever.

2. A cigarette lighter and dispenser, comprising in combination, a container for cigarettes, an automatically operated lighting element in the container, a wick at one end of the lighting element, a flint and steel adjacent the wick, a shaft upon which the wheel is mounted, a gear fitted on the shaft, a vertically movable rack in mesh with the gear, an operating rod integral with the rack, a push-button at one end of the operating rod outside of the container, a piston mounted on the other end of the rack bar, a cylinder in which the piston is slidably fitted, a helical spring in the cylinder below the piston, a projection integral with the rack bar, a trigger adapted to cooperate with said projection, and a trip bar for the trigger extending outwardly through the side wall of the container, together with a leaf spring adapted to cooperate with the lower face of the projection, said leaf spring having a curved end allowing the projection to ride beneath the same upon downward movement, and latching the same upon initiation of an upward movement, a pair of integral lugs on the rack bar, a lever pivotally mounted adjacent the rack bar, a pin in one end of the lever between the lugs, and a cigarette expelling paddle at the other end of the lever.

In testimony whereof I affix my signature.

NILS ARVIDSSON.
